AUTOMATIC CONTROL FOR THE ROLL
PRESSURE DEVICE OF FLATWORK IRON-
ERSHarvey J. Shirley, Norwood, Ohio, assignor to
The American Laundry Machinery Company,
Cincinnati, Ohio, a corporation of Ohio

Application January 31, 1938, Serial No. 187,845

3 Claims. (Cl. 38—4)

This invention relates to ironing machines of the type in which the work is carried between a heated ironing member and a series of padded ironing rolls adjustable or movable into and out 5 of ironing relation with said member. The invention has to do with the mechanism for so moving the rolls, which is designed for automatic control after it is set in operation by the operator.

The invention is an improvement upon the 10 mechanism shown, described and claimed in an application for Automatic pressure control for flatwork ironers, Serial No. 187,826, filed of even date herewith by Norman S. McEwen and Shirley C. Ward, to which reference may be had for a 15 more complete description if desirable or necessary. According to the invention of said application, roll adjusting movement toward and from the ironing member or chest is produced by clutch actuated reversing mechanism controlled 20 by a hand lever. Movement of the hand lever in one direction couples the clutch and advances the rolls toward the chest, the advance motion being terminated automatically by cam devices. Movement of the hand lever in the opposite direction also couples the clutch but the rotation 25 is in the opposite direction and the rolls are moved away from the chest, the operation being terminated at will by the operator and not automatically.

The present invention aims to improve the 30 mechanism of said application by providing automatic termination of the roll pressure relieving operation for the purpose of avoiding possible injury to the machine in case the operator neglects to return the control lever to neutral position.

A further object of the invention is to provide 35 improved cam means for automatically controlling both advance and retraction of the rolls with reference to the chest, such cam means being of improved form including ways or slots for positive lever operation and avoiding the necessity of utilizing any guide for the lever itself.

A further object is to provide cam control 40 means of the kind described including adjusting means enabling the mechanism to be set for the production of any desired pressure effect and also including limiting walls for determining the extent of control movement of the hand lever.

A further object is to generally improve the 45 mechanism so as to retain all the advantages described in said application and in addition, automatic control of the pressure relieving operation and with certainty of correct operation of all of 50 the parts.

Further objects of the invention are in part obvious and in part will appear more in detail hereinafter.

In the drawings, which represent one suitable embodiment of the invention, Fig. 1 is a 5 side elevation of an ironing machine with the invention applied thereto; Fig. 2 is a plan view, on a larger scale, of the control devices, parts being in section on the line 2—2, Fig. 1, the parts 10 being shown in their positions with pressure applied; Fig. 3 is a detail elevation of the control cam devices, with the parts adjusted to produce relatively heavy pressure; Fig. 4 is a development of the combination control cam; Fig. 5 is a view corresponding to Fig. 3, showing the parts 15 adjusted to give less pressure; Fig. 6 is a similar view, showing the cam in pressure-off position; Fig. 7 is a plan of the parts shown in Fig. 6; and Fig. 8 is a detail sectional elevation on the line 8—8, Fig. 7.

While the invention may be applied to any form 20 of ironing machine in which a padded roll or rolls is applied to an ironing member for producing the ironing effect, such as one where the ironing member is a large heated smooth surfaced roll, for convenience and in no sense of limitation the invention has been shown applied to 25 a machine of the roll and chest type.

The machine shown comprises a suitable frame 30 supporting a hollow heated grooved ironing member or chest 2, the concavities of which are designed to receive the several padded rolls 3 all driven in the usual manner by gearing marked generally 4 and including a main shaft 5. The rolls are moved into and out of the pressure applying position shown by the usual vertically 35 movable pressure bars 6 by which they may be lifted out of the concavities of the chest to remove their padded surfaces from contact with the heated chest surfaces, or they may be lowered 40 into contact therewith so as to apply the desirable degree of pressure for the ironing operation.

Pressure bars 6 are operated by lifting rods 7 45 pivoted to them, said rods at their lower ends having straps 8 embracing eccentrics 9 on cross shafts 10 each provided with a worm gear 11 driven by a worm 12 on a longitudinally extending shaft 13 driven by gears 14, 15, from a shaft 16. Said shaft at one end is provided with a hand wheel 17 for hand operation or adjustment of the 50 parts when necessary or desirable, and at its opposite end is provided with connections to a suitable clutch controlled reversing mechanism, such as the usual form indicated generally at 18, Fig. 2. This mechanism, briefly described, 55

- comprises a bevelled driven pinion 19 fast on shaft 16 and coupled to two opposite axially aligned loose bevel pinions 20, 21 journalled on a hollow shaft 22 provided with driving connections, 5 such as the sprocket 23 connected by a chain 24 to a sprocket 25 on the main shaft 5. Within the hollow shaft 22 is slidable a rod 26 having a clutch member 27 extending outwardly through elongated slots 28 in the shaft 22 and designed to 10 be engaged selectively with clutch teeth 29 on the inner ends of the two loose pinions 20, 21 to rotatably drive the shaft 16 in one direction or the other according to which pinion, 20, 21, becomes the active driving member. Rod 26 is 15 shifted back and forth, longitudinally, to produce drive in one direction or the other, by a pivoted lever 30 provided at one end with a fork 31 engaging a grooved collar 32 on the rod, and at its other end with a handle 33. Lever 30 normally occupies an intermediate or neutral 20 position marked A, Fig. 2, but can be moved selectively to either of two end positions, to-wit, the pressure producing position marked B and the pressure relieving position marked C.
- 25 To automatically operate the clutch in the manner to be described, and as illustrated in some measure in the said copending application, the present invention provides cam means operated by a part of the roll adjusting mechanism, such 30 as shaft 10, and effective upon lever 30, as at an abutment pin or roller 34, Fig. 8. Of course the several eccentrics 9 are all fixed to the shafts 10, as by keys 35, Fig. 8, so that they are relatively timed and in step with each other, as will 35 be readily understood. In the arrangement here shown, the clutch operating means includes two cam members, to-wit, a pressure relieving cam member 36 and a pressure producing cam member 37, Figs. 2 and 8.
- 40 Pressure relieving cam member 36 is fixed or non-adjustable with reference to shaft 10. Indeed, in the arrangement shown it is integral with the eccentric 9 at this particular corner of the machine, said eccentric 9 forming the hub 45 for the cam and the key 35 permanently fixing the cam member with reference to shaft 10.
- 45 The pressure producing cam member 37, however, is rotatably adjustable with reference to shaft 10, having a flange or wall 38 lying in a plane normal to the axis of shaft 10 and provided with holes 39 to receive securing bolts 40 passing through elongated slots or openings 41 in a wall of the fixed cam 36. By loosening the bolts 40 and turning cam member 37, it may be 50 adjusted to various positions around the axis of shaft 10 and fixed in any position by tightening the holding bolts 40, thereby to secure any desired degree of pressure, as will appear. The exact 55 degree of pressure may be indicated in any suitable manner, such as by a scale 42 on the fixed cam member 36, one end edge 43 of the adjustable cam member 37 serving as a pointer with reference to the divisions of the scale 42, as shown 60 in Figs. 3 and 5.
- 65 The cam members 36 and 37 are of special form, their outer cylindrical, or partly cylindrical peripheral surfaces being provided respectively with grooves or channels 44, 45, each having a straight portion and an inclined or cam portion 70 as shown in Fig. 4. These channels are defined by inner walls 46 of moderate height and outer walls 47 of increased height and which serve as stops to limit adjusting motion of the hand lever and insure registration of its abutment 34 with the desired cam groove.

The mechanism described operates as follows: Fig. 2 in full lines shows the lever 30 in neutral position with the rolls applied with full pressure to the chest. The abutment 34 of said lever lies in the channel 45 of the adjustable cam 37 at 5 position A, Fig. 4.

To relieve the roll pressure, or elevate the rolls out of the concavities in the chest, lever 30 is grasped by the operator, is lifted slightly to raise its abutment 34 above the upper edge of the 10 groove walls 46 (lever 30 being sufficiently flexible or the pivotal joint in the lever supporting bracket 48 being sufficiently sloppy for the purpose) and said lever is moved over to position C, Fig. 2, bringing the lever abutment 34 to position C, 15 Fig. 4. The lever is released and its abutment drops into the straight portion of cam groove 44. The clutch has been coupled and shaft 16 is driven in the proper direction to elevate the pressure bars 6. At the same time shaft 10 rotates the 20 cams, the effect being to move the lever abutment 34 from position C, Fig. 4 to position A, where the clutch is uncoupled and the roll adjusting movement stops, with the rolls fully out of contact with the chest. This operation is performed 25 whenever it is desired to prevent unnecessary heating of the rolls by the chest, such as might damage the padding, say at lunch hour or when the machine is out of operation for a short period, as well as at the close of the day. 30

When work is resumed and it is desired to apply the rolls with pressure to the chest, lever 30, again in the neutral position A, Fig. 2, is again raised, but this time it is moved in the opposite direction or to position B, Fig. 2, which moves its abutment 35 34 from position A to position B, Fig. 4. Upon release of the lever its abutment drops into the straight portion of cam groove 45. The clutch has been coupled and roll adjusting movement proceeds with the rolls advanced toward the chest 40 until finally, by the effect of the inclined portion of cam groove 45, the lever abutment 34 is returned to the neutral position A, Fig. 4, which uncouples the clutch and terminates the roll adjusting operation, with the rolls applied to the 45 chest with that degree of pressure determined by the setting of the adjustable cam 37. Of course, if the padding packs down in use and it is desired to give the rolls additional adjustment so as to maintain the same pressure, or if it is desired 50 to increase the pressure, the cam 37 is adjusted to a new position in the manner before described.

This mechanism enables both adjustments of the rolls, toward and away from the chest, to be initiated by the operator, but automatically terminates each operation independently of operator judgment. As a result, there is no liability of the operator initiating the pressure relieving operation and then omitting to manually return the lever to neutral position so that the eccentrics 8 not only carry the rolls away from the chest but go further and return them to the chest, as will be readily understood.

The cams are of special form avoiding any necessity of guiding means for the operating 65 lever. Their peripheral grooves positively actuate and control the movement of the operating lever when actuated by the machine, and the high flanges defining the outer edges of the cam grooves form limiting stops which insure registration of the lever abutments of the cam groove. 70

One important advantage of the invention is the simplicity and ease with which it may be attached or adapted to machines already in use. That is to say, there are already in the field many 75

ironing machines of this type each provided with four of the eccentrics 9 for adjusting the rolls and a clutch operating lever 30 which is entirely manually operated, being moved by the operator 5 to either of its clutch closing positions and then being manually returned when the desired roll adjusting movement is completed. By removing the proper one of the eccentrics 9 on such a machine and substituting therefor the new eccentric 10 described herein, with the cam members 36, 37 attached thereto, and providing lever 30 with a suitable abutment member, such as shown at 34, the manually controlled machine may be readily converted to a semi-automatic machine. 15 The roll adjusting movement is initiated manually and terminated automatically, as will be readily understood. Of course, in adapting the invention to such a machine, and setting it up, the time of termination of pressure release is 20 determined by the timed relation of cam member 36 to eccentric 9, these parts being integral with each other, and the timing of the production of desired pressure is produced by adjustment of the cam member 37 in the manner herein described. 25 Further advantages of the invention will be apparent to those skilled in the art.

What I claim is:

1. In apparatus of the character described having a chest and a cooperating roll adjustable toward and from the chest, the combination of roll adjusting mechanism, comprising a clutch operated reversible driving shaft for adjusting the roll, two cams operated by said shaft, a clutch operating lever having a neutral position and movable selectively to either of two clutch coupling positions, in one of which said lever meets one cam and the roll is advanced and in the other of which said lever meets the other cam and the roll is retracted, the met cam being adapted upon rotation of said shaft to return the lever to neutral position when roll adjustment is completed, the active parts of said cams extending peripherally of said shaft, and that cam which terminates roll advancing movement being adjustable around the shaft axis to vary the time of completion of lever return movement. 45

2. In apparatus of the character described hav-

ing a chest and a cooperating roll adjustable toward and from the chest, the combination of roll adjusting mechanism, comprising a clutch operated reversible driving shaft for adjusting the roll, two cams operated by said shaft, a clutch operating lever having a neutral position and movable selectively to either of two clutch coupling positions, in one of which said lever meets one cam and the roll is advanced and in the other of which said lever meets the other cam and the roll is retracted, the met cam being adapted upon rotation of said shaft to return the lever to neutral position when roll adjustment is completed, each cam having a channel adapted to receive an abutment portion of said lever and the side walls of which form its active operating parts, the active parts of said cams extending peripherally of said shaft, and one of said cams being rotatably adjustable around the shaft axis to vary the time of completion of lever return movement. 5

3. In apparatus of the character described having a chest and a cooperating roll adjustable toward and from the chest, the combination of roll adjusting mechanism, comprising a clutch operated reversible driving shaft for adjusting the roll, two cams operated by said shaft, a clutch operating lever having a neutral position and movable selectively to either of two clutch coupling positions, in one of which said lever meets one cam and the roll is advanced and in the other of which said lever meets the other cam and the roll is retracted, the met cam being adapted upon rotation of said shaft to return the lever to neutral position when roll adjustment is completed, each cam having a channel adapted to receive an abutment portion of said lever and the side walls of which form its active operating parts, the active parts of said cams extending peripherally of said shaft, and one of said cams being rotatably adjustable around the shaft axis to vary the time of completion of lever return movement, that wall of each channel remote from the neutral position of said lever being higher than the other wall to form a stop to prevent abnormal lever movement. 30 35 40 45

HARVEY J. SHIRLEY.
